INVENTOR
James G. Nolen,

BY
Harold D. Penney

ATTORNEY

UNITED STATES PATENT OFFICE.

JAMES G. NOLEN, OF NEW YORK, N. Y.

VIBRATION MODIFIER FOR DIAPHRAGMS.

Application filed January 22, 1925. Serial No. 3,977.

The present invention relates to tone modifiers for sound reproducing instruments, and particularly to a tone modifier preferably applied to a phone receiver, and one object of the invention is to provide a tone modifier which may be used in conjunction with the diaphragm of the phone receiver, the invention in some respects being a modified application of the device 10 shown in my copending United States application Serial No. 755,213, filed Dec. 11, 1924.

One of the advantages of my present invention is that by its use there is caused to 15 be formed adjacently to the diaphragm proper of the receiver a restrained air chamber. The advantage of this is that by restraining the air within a chamber formed by two diaphragms, one of which is the 20 phone receiver diaphragm, a form of tension is imposed upon the receiver diaphragm, thereby giving it greater sensitivity to the higher audio frequency of oscillation, and through this tensioning causing the receiver diaphragm to be a livelier acting diaphragm. 25

Another advantage is that due to the construction of my modifier a small aperture is formed through which the pulsations of air from said chamber may emit, and this 30 therefore acts for greater concentration of the tone vibrations as they issue from the opening.

Another advantage is the provision of simple means by which through modification 35 of the vibration tensions upon the receiver diaphragm a modification of tone may be had, due to the use of a baffle-like vibration control means whereby the aperture or apertures through which the sound emits may be varied to any desired degree.

Another advantage of the invention is that its form of structure is such that it may be 40 removably mounted in a phone receiver as desired.

I attain the above object and such other objects as may later appear herein by the invention several of the many possible embodiments of which are described by way of example in the subjoined specification and 45 shown in the drawing accompanying the

specification in which Fig. 1, is a fragmental side view, partly in section, of a phone receiver with the tone modifier applied thereto.

Figure 2, is a detail sectional view of one form of the tone modifier.

Figure 3, is a plan view of the form of tone modifier shown in Fig. 2.

Figure 4, is a detail sectional view of another form of the tone modifier.

Figure 5, is a detail plan view of the form 60 of tone modifier shown in Fig. 4.

Figure 6, is a detail sectional view of another form of the tone modifier.

Figure 7, is a detail plan view of the form 65 of the tone modifier shown in Fig. 6, and

Figure 8, is a detail sectional view of another form of the tone modifier.

Similar reference characters denote similar parts throughout the several views.

Referring to Fig. 1, there is shown a portion of a phone receiver having the cap 10 thereon provided with the sound opening 11 and the diaphragm 12 stretched across the sound opening and suitably spaced away from the adjacent under surface of the cap. 70

The tone modifier which is insertible in the opening 11 of the phone receiver, consists of the disk body 13 having the flange 14 over which the marginal portion of the disk body extends and having the opening 80 15, and having supported in the disk body the protector or protective disk 16 adapted to permit passage of air therethrough, and having supported in the disk body the modifier diaphragm 17 provided with the aperture 18. The protective disk 16 is retained in the disk body by the ring 19 and is spaced away thereby from the diaphragm 17, the diaphragm 17 being retained in the disk body by the ring 20 and spaced away thereby 85

from the horizontal plane of the free end of the flange 14 of the disk body, a restrained air chamber 21 being formed between the upper surface of the phone receiver diaphragm 12 and the under surface 90 of the modifier diaphragm 17, the air being emitted therefrom by the aperture 18 of the modifier diaphragm.

Referring to Figs. 2 and 3, the construction of the tone modifier is the same as 100

shown in Fig. 1, except that the protector or protective disk 22 is of wire gauze or other suitable reticulated material.

In the construction shown in Figs. 4 and 5, the disk body 23 instead of being provided with a single control aperture, is provided with a plurality of apertures 24 which are registerable with the apertures 25 of the top plate 26, the top plate being recessed on its under side to provide a marginal portion having therein an annular groove or rabbet 27 which receives the extended marginal portion of the disk body 23 whereby the top plate 26 may be slidably rotated or turned on the disk body 23 for varying the registration of the apertures 24 and 25, the top plate thus serving to regulate the volume of air passing through the aperture 24 of the disk body 23, while the disk portion of the disk body serves as a protector or protective disk for the diaphragm 27 having the central aperture 28. The flange of the disk body 23 is provided with an interior annular shoulder 29 against the under side of which the modifier diaphragm 27 bears, and is spaced away thereby from the under side of the disk portion of the disk body, and is retained in position and spaced away from the horizontal plane of the free end of the flange of the disk body by the ring 30, said flange being inwardly turned at its interior lower edge for holding the ring in place, this spacing away of the diaphragm by the ring 30 causing the formation, when the device is in operative position in the phone receiver, of a restrained air chamber similar to the air chamber 31 seen in Fig. 1, the air being emitted from said chamber through the aperture 28.

Referring to Figs. 6 and 7, the tone modifier shown consists of the disk body 31 having the downturned flange 32 and provided with the relatively large central opening 33. The diaphragm 34, having the central aperture 35, is of silk and is stretched across the opening 33 on the under side of the margin of the disk body, being held in place by the band 36 and spaced away thereby from the horizontal plane of the free end of the flange of the disk body, this spacing away of the diaphragm by the band causing the formation, when the device is in operative position in the phone receiver, of a restrained air chamber similar to the air chamber 21 seen in Fig. 1, the air from said chamber being emitted by the aperture 35.

Referring to Fig. 8, the tone modifier shown consists of the disk body 37 having the opening 38 and a thin intramarginal portion 39 adjacent thereto which is extended as a thick edge portion 40 of the disk body overlying the downturned flange 41. The modifier diaphragm 42 of rubber having the central aperture 43 is stretched over the opening 38 on the under side of the intra-

marginal portion 39, and is held in place and spaced away from the horizontal plane of the free end of the flange 41, by the ring 44, this spacing away of the diaphragm by the ring causing the formation, when the device is in operative position in the phone receiver, of a restrained air chamber similar to the air chamber 21 seen in Fig. 1, the air from said chamber being emitted by the aperture 43.

Having thus described my invention, it should be understood that there may be modifications thereof and variations therein without departing from the spirit of the invention, or exceeding the scope of the appended claims.

What I claim and desire to protect by Letters Patent is:

1. In combination with a phone receiver having a cap provided with a sound opening, a tone modifier comprising a disk body having apertures therethrough and having an annular transverse flange insertible in the opening of said cap, a top plate slidably rotatably movable on said disk portion and having apertures therethrough normally registering with the apertures of the disk portion, an apertured diaphragm in the interior of said flange extending parallel to said disk portion, means for spacing the diaphragm away from the under side of the disk portion, and means for securing the diaphragm in the flange and spacing the same away from the plane of the free end of said flange, said diaphragm when said flange is inserted in the opening of said cap forming with the diaphragm of the phone receiver a chamber for restraining air between the diaphragms.

2. In combination with a phone receiver having a cap provided with a sound opening, a tone modifier comprising a disk body having a disk portion with apertures therethrough and having an annular transverse flange insertible in the opening of said cap, a top-plate slidably rotatably movable on said disk portion and having apertures therethrough normally registering with the apertures of said disk portion, an apertured diaphragm in the interior of said flange extending parallel to said disk portion, an annular shoulder on the interior of said flange for spacing the diaphragm away from the under side of the disk portion, and a ring for securing the diaphragm in the flange and spacing the same away from the plane of the free end of said flange, said diaphragm when said flange is inserted in the opening of said cap forming with the diaphragm of the phone receiver a chamber for restraining air between the diaphragms.

3. In combination, a telephone receiver including an ear piece having an opening therein, and a diaphragm near the opening, a disk body in the opening having a top wall with an aperture therein; and a modi-

- 5 fier diaphragm across said body spaced from said top wall; said modifier diaphragm being of less than one-fourth the diameter of the phone diaphragm, whereby the amount of movement of the phone diaphragm is amplified or multiplied in the modifier diaphragm.
- 10 4. In combination, a telephone receiver including a concaved ear piece having a small central opening therein; and a diaphragm near and parallel to the plane of the opening and over four times larger in diameter than the opening; a disk body inserted in the opening; and a modifier smaller than said opening disposed across said body.
- 15 5. In combination, a telephone receiver including an ear piece having a small opening therein; a disk body inserted in the opening; and a modifier diaphragm disposed across said body.
- 20 6. In combination, a telephone receiver including an ear piece having an opening therein; a disk body detachably disposed in the opening; and a modifier diaphragm across said body.
- 25 7. In combination, a telephone receiver including an ear piece having an opening therein, and a diaphragm near the opening; a disk body in the opening having a flange received and frictionally held in said opening; and a modifier diaphragm across said body.
- 30 8. In combination, a telephone receiver including an ear piece having an opening therein; a diaphragm protector disposed across said opening; and a modifier diaphragm across said opening below said top protector.
- 35 9. In combination, a telephone receiver including an ear piece having an opening therein; and a silk modifier diaphragm across said opening.
- 40 10. In combination, a telephone receiver including an ear piece having a small central opening therein, and a diaphragm near the opening; a disk body in the opening having a protecting top wall with an aperture having a flange received in said opening; and a silk modifier diaphragm across said body spaced from said top wall and provided with a small aperture therein.
- 45 11. In combination, a telephone receiver including an ear piece having an opening therein; a disk body across the opening having a top diaphragm protector substantially out of contact with the ear in normal use; and a modifier diaphragm across said body below said protector.
- 50 12. In combination, a telephone receiver including an ear piece having a small central opening therein, and a diaphragm near the opening; a disk body in the opening substantially out of reach of the ear in normal use; and a modifier diaphragm across said body.
- 55 13. In combination, a telephone receiver including an ear piece having an opening therein; a modifier diaphragm across said opening and provided with an aperture; and a baffle alined with said aperture. 70
- 60 14. In combination, a telephone receiver including an ear piece having an opening therein; a disk body in the opening having a top wall with an aperture therein; and a modifier diaphragm across said body below said top wall and provided with an aperture. 75
- 65 15. In combination, a telephone receiver including an ear piece having an opening therein; a disk body in the opening having a top wall with an aperture therein; and a modifier diaphragm across said body below said top wall and provided with an aperture out of alinement with the aperture of the top wall. 80
- 70 16. In combination, a telephone receiver including an ear piece having an opening therein; a disk body about the size of said opening and inserted in the opening in a position substantially out of reach of the ear and having a top wall entirely across the body provided with apertures remote from the center of the body and having a flange received in and detachably frictionally held in said opening and provided with an outwardly faced annular shoulder on its inner face in a plane near and parallel to said top wall; and modifier diaphragm disposed across said body spaced from and protected by said top wall and provided with a central aperture out of alinement with the 90 aperture of the top wall and plate whereby said top wall between the apertures thereof acts as a baffle. 95
- 75 17. In combination, a telephone receiver including an ear piece having an opening therein; a disk body in the opening having a top wall with an aperture therein of adjustable size; and a modifier diaphragm across said body below said top wall. 100
- 80 18. In combination, a telephone receiver including an ear piece having an opening therein; a disk body about the size of said opening and inserted in the opening and having a top wall entirely across the body provided with apertures remote from the center of the body and having an inner flange received in and detachably frictionally held in said opening and provided on its inner face with an outwardly faced annular shoulder in a plane near and parallel to said top wall; a top plate rotatably mounted on the top wall in a position substantially out of reach of the ear and having apertures registerable with the apertures of the top wall; and a modifier diaphragm across said body below said top wall. 110 115 120
- 85 19. In combination, a telephone receiver including an ear piece having an opening therein, and a diaphragm near the opening; 125 130

a disk body in the opening having a diaphragm-protector with an aperture therein; and a modifier diaphragm across said body spaced from said protector and provided with a small aperture.

20. In combination, a telephone receiver including an ear piece having an opening therein; a disk body about the size of said opening and inserted in the opening in a position substantially out of reach of the ear and having a flange received in and detachably frictionally held in said opening and provided with an inturned edge, and on its inner face with an outwardly faced annular shoulder in a plane near and parallel to said body; a ring held in said flange by said inturned edge; and a modifier diaphragm held on said shoulder by said ring spaced from the top plane of the body.

21. In combination, a telephone receiver including a concaved ear piece having a small central opening therein, and a dia-

phragm near and over four times as large in diameter as the opening; a disk body inserted in the opening in a position substantially out of reach of the ear and having a top wall entirely across the body provided with apertures remote from the center of the body and having a flange received in and detachably frictionally held in said opening and provided with an outwardly faced annular shoulder on its inner face in a plane near and parallel to said top wall; a top plate rotatably mounted on the top wall and having apertures registerable with the apertures of the top wall; and a modifier diaphragm mounted on said shoulder and protected by said top wall and provided with a central aperture out of alignment with the aperture of the top wall.

Signed at New York in the county of New York and State of New York this 21st day of January, A. D. 1925.

JAMES G. NOLEN.
